United States Patent Office

Des. 227,838
Patented July 24, 1973

227,838

DRESSER WITH SCULPTURED LATTICE MOTIF OR THE LIKE

Joseph E. Adkinson, 3807 Leland St.,
Chevy Chase, Md. 20015

Filed Feb. 4, 1972, Ser. No. 223,818

Term of patent 14 years

Int. Cl. D6—04

U.S. Cl. D6—154

FIG. 1 is a view in front elevation of a dresser showing my design.

FIG. 2 is a view in side elevation of the dresser of FIG. 1.

FIG. 3 is a top plan view of the dresser of FIG. 1.

The back of the dresser is conventionally flat and the side of the dresser not depicted is the same as the side shown in FIG. 2.

I claim:

The ornamental design for a dresser with sculptured lattice motif or the like, substantially as shown and described.
